UNITED STATES PATENT OFFICE.

GEORGE H. BARBOUR, OF PITTSBURGH, PENNSYLVANIA.

COMPOSITE STRUCTURE.

1,101,983.

Specification of Letters Patent. Patented June 30, 1914.

Application filed February 10, 1911. Serial No. 607,853.

To all whom it may concern:

Be it known that I, GEORGE H. BARBOUR, of Pittsburgh, in the county of Allegheny and State of Pennsylvania, have invented a new and useful Improvement in Composite Structures, of which the following is a full, clear, and exact description, reference being had to the accompanying drawings, forming part of this specification.

10 My invention relates to structures formed of reinforced concrete, slag or other plastic material.

The object of my invention is to provide a frame work of a minimum thickness for a given strength and quantity of material, interlaced at proper intervals with bars registering with holes in the frame work, and which may be secured to the frame work at the desired points.

20 Another object of my invention is to provide a frame work whose elements are of the same web depth, or flange width and web depth and assembled in such a manner that all of their component parts except the 25 gusset plates, and a portion of the securing devices lie within and between two parallel planes coinciding with the inner faces of the gusset plates. The gusset plates on the opposite side of the frame work being spaced 30 apart a distance equal to the web depth or flange width of the elements, so that the frame work may be used for a guide and support for the forms used to mold the concrete or plastic filling.

35 Still another object of my invention is to provide a shape to be used, as a stud, beam or rafter, whose contour is such that a tongue and groove connection is provided between the frame work and the adjacent 0 panels of concrete.

A further object of my invention is to provide a column section of large cross-sectional area, which is so shaped that when placed it will be concealed within a wall whose thickness is less than the depth or width of the column, without breaking the continuity of the face of the wall or partition.

Another object of my invention is to provide devices embedded in the concrete or plastic filling, preferably secured to the bars or frame work of the structure. These devices extend beyond the face of the wall and are arranged to anchor an article to said wall.

55 Still a further object of my invention is to provide an air space between the face of

the wall and the lath, brick, or other material, by interposing thimbles, strips or spreaders between the wall and the article secured thereto.

60 The precise nature of my invention will be best understood by reference to the accompanying drawings, which will now be described, it being premised, however, that various changes may be made in the details 65 of construction and general arrangement of the parts, without departing from the spirit and scope of my invention as defined in the appended claims.

70 In the accompanying drawings I have shown my invention applied to one type of building, and in which:

Figure 1 is a sectional elevation of a portion of one type of building constructed in accordance with my invention; Fig. 2 is a 75 front elevation of a portion of the frame work; Figs. 3 and 4 are respectively sectional and side elevations of a frame work of another form of structure; Fig. 5 is a sectional plan view showing one form of securing 80 anchors to the concrete for fastening articles to the wall; Fig. 6 is a vertical section of the same; and Fig. 7 is a perspective view partially in section showing one form of applying staples and forms to the frame work 85 for receiving the concrete filling.

In the drawings, the numeral 2 designates a girder forming the frame work for the basement of the building. This girder is composed of a sill 3, having a web 4, and upwardly extending flanges 5.

6 is a beam forming the upper chord of the girder 2, which in this case has been provided with upwardly and downwardly extending flanges in the same plane as the 95 flanges 5 of the sill 3.

7-7 are struts connected to the upwardly extending flange 5 of the sill 3 and the downwardly extending flanges of the chord 6 by means of the gusset plates 8.

9 are columns within the basement arranged to support the girders 10 for supporting the first floor of the building. As can be seen by reference to the drawings, the flanges of the columns and the girders have 105 been perforated to receive reinforcing bars 11, which may be secured to the various members forming the frame work, or may merely extend through the openings in said members.

110 The frame work of the first story of the building has been formed by means of the

vertical elements 12 having flanges which coincide with the flanges of the chord 6, and also with the body of the eave support 13, and are secured thereto by means of the 5 gusset plates 8^a and bolts or rivets extending through the several members and the gusset plates. These various elements are also perforated to receive reinforcing bars, as clearly illustrated in Figs. 1 and 2. The reinforcing 10 bars may be round or square, or twisted or any of the usual deformed sections.

The eave support is provided with orifices and projecting through these orifices from one support to the support on the opposite 15 side of the building are the tie rods 14, which are secured in place by means of the nuts 15.

16 are the reinforcing bars for the roof, which may be held in position by means of a girder 17, which may form a permanent 20 portion of the structure, or which may be removed after the concrete has been placed to form the roof.

18 are hangers connected to the reinforcing bars 16 and are arranged to support the 25 tie rods 14, together with the ceiling lath 23 which has been connected thereto by the wires which has been connected thereto by the wires 27.

Openings for windows or doors may be 30 provided by securing transverse members 20 to the upright members 12, as indicated in Fig. 2. These openings may be stripped with wood bolted to the several members and to which the frame to the window or to the 35 door may be secured.

The building is erected in the following manner: The framing is first erected by securing the various members to each other by means of the gusset plates 8, 8^a and rivets 40 or bolts, so that the only portion of the framing extending beyond the outer faces of the flanges of the elements are the rivet and bolt heads and nuts and gusset plates. After the framing has been erected, the reinforcing 45 members are placed in position and forms for the concrete are then secured to the framing. These forms may be of wood or metal, wired to each other and to the framework, or reinforced concrete slabs 50 which may be secured to the frame work and to each other by lacing and after which the filling material is placed between the frame elements and the outer faces of the flanges of the frame work. I prefer to use vertical 55 elements, such as shown in Figs. 5 and 7, which are provided with grooves to permit the concrete to form a perfect interlock with the frame work, and form a tongued and grooved connection between adjacent slabs 60 of concrete. I also prefer to place anchoring devices in the wall and preferably on the reinforcing bars, as clearly illustrated on Figs. 5, 6 and 7, which extend beyond the outer face of the flanges and to which I may 65 secure a strip or distance piece 21, as indi-

cated in Fig. 6, or thimbles 22, as indicated in Fig. 1.

23 designates the lath which is secured to the wall by means of the anchoring devices, and which has been spaced from said 70 wall by means of the strips or spreader 21, or thimbles 22. This lath is also secured to the stay rods 14 by means of the wire 27, and is provided to support the usual bolster for finishing the interior of the structure. 75

In Fig. 6, I have shown an anchor device 25 extending through the outer face of the wall and which may be used for securing plaster, brick or other veneer, as indicated at 26 for the outer face thereof. 80

In Figs. 3 and 4, I have illustrated columns which are arranged to lie in the wall of the building at the intersection of the walls or partitions, and in which I have placed the webs of said sections at an angle 85 of 45° to the wall or partition, so that the open portion between the flanges of the section can be thrown into the room which has been divided off by the partition. In this construction the lath can be run into the 90 space between the flanges so that the corner of the room will not be broken up by a column whose width and depth is considerably greater than the thickness of the wall or partition. 95

The advantages of my invention result from the provision of the frame work in which all of the elements of said frame lie within two planes, and which elements are perforated to receive the reinforcing bars. 100 By the provision of a frame in which all of the elements of the frame lie within the two planes, I am enabled to use the frame work for the support for the molds for the filling material, and by forming the frame 105 work which has been previously perforated to receive the reinforcing bars, I am enabled to erect a structure in which all of the reinforcing bars will be placed at the proper point designated by the architect or engineer, in designing the building, and which can be placed by an ordinary laborer. 110

By means of the anchoring devices, I am able to rigidly secure lathing or any building material to the walls of the building, and by means of my strips, spreaders or thimbles, I can readily and cheaply furnish an air space between the wall and article attached thereto. Another advantage results from my ability to embed 115 a latticed girder in the concrete or plastic material wherever necessary, which is especially desirable in basement or foundation walls to insure against unequal settling of the walls. 120

I desire it to be understood, that where I use the term wall, I refer to any portion of a structure which divides one portion from another, whether it is a partition, outer wall, floor, ceiling or roof. It will also be under- 125

stood that elements claimed are adapted to be used in structures other than buildings.

I claim:—

1. A composite building structure, comprising a plurality of concrete slabs and a metallic frame-work, said frame-work comprising a plurality of structural elements having webs and flanges on the ends of the webs, said flanges extending parallel with the walls of the building, connecting members for connecting the frame-work on one side of the building to the frame-work on the other side thereof, concrete filling between the structural elements, said concrete fillings having tongues on one end engaging grooves in the structural elements, and grooves along the opposite edges in which the structural elements are seated, the tongues on the sections extending beyond the edges of the adjacent sections; substantially as described.

2. A composite building structure comprising concrete and a metallic frame work, said frame work comprising a plurality of structural elements having webs and flanges on the ends of the webs, said flanges extending parallel with the walls of the building, connecting members secured to the several portions of the frame work for holding them in position with relation to each other, reinforcing rods extending from one structural element to an adjacent structural element, concrete filling between the webs and flanges of adjacent structural elements, each concrete section having tongue and groove engagement with an adjacent concrete section, and anchoring devices embedded in the concrete in engagement with the reinforcing members and extending beyond the face of the concrete; substantially as described.

3. A composite building structure comprising concrete and a metallic frame work, said frame work comprising a plurality of structural elements having webs and flanges on the ends of the web, said flanges extending parallel with the walls of the building, connecting members secured to the several portions of the frame work for holding them in position with relation to each other, reinforcing rods extending from one structural element to an adjacent structural element, concrete filling between the webs and flanges of adjacent structural elements, each concrete section having a tongue and groove engagement with an adjacent concrete section, and anchoring devices embedded in the concrete in engagement with the reinforcing members and extending beyond the face of the concrete, the face of the concrete being on a line with the outer faces of the flanges of the structural elements; substantially as described.

4. A composite building structure, comprising a plurality of concrete slabs and a metallic frame-work, said frame-work com-

prising a plurality of structural elements having webs and flanges on the ends of the webs, said flanges extending parallel to the walls of the building, there being a plurality of spaces formed between the structural elements and a concrete panel within each of said spaces, each of said panels having a tongue along one edge and a groove along the opposite edge, the tongues and grooves of adjacent panels interlocking with the structural shape between them, the tongue on one of said panels extending beyond the edge of the adjacent panel; substantially as described.

5. A composite building structure, comprising a plurality of slabs and a metallic frame-work, said frame-work comprising a plurality of structural elements having webs and flanges on the ends of the webs, said flanges extending parallel with the walls of the building, there being a plurality of spaces formed between the structural elements, reinforcing rods extending from one structural element to another structural element, and concrete fillings within said spaces, said fillings having a tongue and groove engagement with each other and the structural element between them, each structural element is seated in the groove in one filling and embraces the tongue of the adjacent filling; substantially as described.

6. A composite building structure, comprising a metallic frame-work in concrete walls, there being partitions within said building, the frame-work having supporting columns at the intersection on the partitions and the junctions between the walls and the partitions, said columns each having a single web at an angle to all of the walls or partitions extending from said junctions, said columns having flanges on both ends of the webs, said flanges having two portions at an angle to each other, the cross-sectional area of the space embraced by said columns being greater than the cross-sectional area of the partitions at the point of intersection; substantially as described.

7. A composite building structure, having a metallic frame work and a plurality of partitions, a supporting column at the junction of said partitions and forming a portion of the frame work, said column having a single web and a plurality of flanges formed integrally therewith and extending at an angle to the web, said web extending diagonally with relation to all of the partitions while the flanges extend parallel to and into the partitions to a point beyond the junction of the partitions; substantially as described.

8. A composite building structure having a metallic frame work formed of a plurality of structural shapes and supporting columns, partitions within said building extending from said columns, each of said columns having a single web at an angle to all parti-

- tions radiating from the junction, and a flange on the end of each web having a portion parallel with the partition adjacent thereto; substantially as described.
- 5 9. A composite building structure having a metallic frame work formed of a plurality of structural shapes, partitions within said building, said frame-work having columns at the junctions of said partitions, each of 45
10 said columns having a single web at an angle to all partitions radiating from the junction, and flanges on each end of the web at an angle to the web and extending into the partitions; substantially as described.
- 15 10. A composite building structure having a metallic frame work formed of a plurality of structural shapes, partitions within said building, said frame-work having columns at the junctions of said partitions, each of said 50 columns having a single web at an angle of forty-five degrees to all partitions radiating from the junction, and flanges on each end of the web at an angle of forty-five degrees to the web and extending into the partitions; substantially as described.
- 20 11. A composite building structure having a metallic frame work formed of a plurality of structural shapes, partitions within said building, said frame-work also having supporting columns at the junctions of said partitions, each of said columns having a single web at an angle to all partitions radiating from the junction, and flanges having right 55 angle projections on each end of the web and extending into the partitions; substantially as described.
- 25 12. A composite building structure, comprising concrete and metallic frame work, partitions within said building, and columns at the intersections of the partitions, said 60 columns having a web and a plurality of 65
30 supporting elements of the frame work, said columns each having a single web and a plurality of integral flanges extending from each end, the web height of the column being greater than the thickness of the partitions and extending at an angle of approximately 45 degrees to the partitions, while the members extending from the ends thereof extend into the partitions and parallel therewith; substantially as described.
- 35 13. A composite building structure comprising concrete and a metal frame work, partitions within said building, columns at the intersections of the partitions, said columns each having a single web and a plurality of bent flange members formed integrally with the web and extending from each end of the web, the web of each of said 70 columns lying at an angle to all of the partitions, while the bent flange members extend into the partitions, a portion of each of said flanges extending in lines which are parallel with their respective partitions, while the other portions extend at right angles to their respective partitions; substantially as described.
- 40 14. A composite building structure comprising concrete and a metal frame work, partitions within said building, columns at the intersections of the partitions, said columns each having a single web and a plurality of 75
35 flanges at each end of the web, each of said flanges having two portions at right angles to each other, and each of said portions being at an angle of 45° to the web; substantially as described.

In testimony whereof, I have hereunto set my hand.

GEORGE H. BARBOUR.
